COLLAPSIBLE CANOPY STRUCTURE

Osvaldo F. Sartori, Sacramento, Calif.

Application December 8, 1950, Serial No. 199,873

3 Claims. (Cl. 135—4)

1

This invention relates to collapsible canopy structures.

An object of this invention is to provide a collapsible canopy structure in which the U-shaped bows each have a two section crossbar extending between the side bars, with the outer ends of the crossbar being pivoted to the side bars and the inner ends of the crossbar being connected together for hinged movement from the position of axial alignment to a collapsed position.

An object of this invention is to provide a collapsible canopy structure wherein the hingedly connected inner ends of the two section crossbar of each U-shaped bow when swung to the axial alignment position are releasably locked together.

A further object of this invention is to provide a collapsible canopy structure wherein stop means is provided on the hingedly connected inner ends of the two section crossbar of each U-shaped bow for limiting the hinged movement to the axial alignment position.

The above and still further objects and advantages of the invention will become apparent upon consideration of the following detailed description of the invention, when taken in conjunction with the accompanying drawings, wherein:

Figure 1 is a side elevational view of a collapsible canopy structure constructed according to the present invention shown detachably secured to a boat and forming a protective hood;

Figure 2 is an elevational view, with parts broken away and shown in section, taken along the line 2—2 of Figure 1;

Figure 3 is an enlarged fragmentary elevational view taken along the line 3—3 of Figure 2;

Figure 4 is a front elevational view of the collapsible canopy structure shown in Figures 1 to 3 and illustrated with the canvas removed, and showing the collapsed position in phantom lines;

Figure 5 is a fragmentary top plan view of a central portion of one of the collapsible bows, showing a lock sleeve for maintaining a bow in its extended position;

Figure 5A is a fragmentary perspective view of the right-hand end portion of the sleeve of Figure 5;

Figure 6 is a fragmentary sectional view taken substantially along the line 6—6 of Figure 5;

Figure 7 is an enlarged, exploded, fragmentary, front elevational view of the collapsible canopy shown in Figure 2;

Figure 8 is an enlarged, fragmentary, sectional view taken along the line 8—8 of Figure 2;

Figure 9 is a perspective view, with parts broken away, of a bracket for detachably securing the canopy structure to the boat;

2

Figure 10 is a fragmentary, elevational view, with parts broken away and shown in section, of a modified form of the collapsible bow of the canopy structures of the present invention;

Figure 11 is an end elevational view of a canopy structure constructed to the present invention supported on the open body of a vehicle, with parts broken away and shown in section;

Figure 12 is a side elevational view of the canopy structure shown in Figure 11, with parts broken away and shown in section;

Figure 13 is a front elevational view of a collapsible awning structure constructed according to the present invention, with parts of the awning cover broken away; and

Figure 14 is a sectional view taken along the line 14—14 of Figure 13.

Referring now more particularly to the drawings, wherein like reference numerals have been used throughout the several views to designate like parts, in accordance with the invention a protective hood 10 for a boat 11 embodies a plurality of U-shaped bows 12 operatively connected together for movement from a position in spaced confronting relation with respect to each other to an extended or expanded position, Figure 1, in diverging relation with respect to each other. Since each of the bows 12 is of like structure, it will suffice to describe only one in detail.

Each of the bows 12 embodies a pair of straight side bars 13 and 14 disposed in spaced, parallel relation with respect to each other, and a two-section cross bar 15 disposed transversely between the side bars 13 and 14 with opposite ends thereof pivotally connected to the side bars 13 and 14 at their outer ends by pins 16. As clearly shown in Figures 5 and 6, a locking hinge 20 pivotally connects and is disposed between the two sections 17 and 17' of the crossbar 15, whereby movement of the side bars 13 and 14 toward each other collapses the crossbar 15 inwardly into a position between the side bars 13 and 14, as illustrated in phantom lines in Figure 4.

The locking hinge 20 illustrated in Figures 5 and 6 comprises a first plate or disc 21 fixed eccentrically on the adjacent end of the section 17' of the crossbar 15 and a bifurcated second plate or disc 22 fixed eccentrically on the adjacent end of the section 17 of the crossbar 15. The plate 21 is received within the bifurcation of the plate 22 and is disposed in abutting and confronting relation with respect to the latter, the plates 21 and 22 being operatively connected together by a hinge pin 23 which extends transversely through the plates and pivotally connects the sections 17 and 17' together for movement from an extended

position in end-to-end aligned relation with respect to each other to a collapsed position between the side bars 13 and 14 in confronting relation with respect to each other. The plates 21 and 22 are provided with a radially extending slot 24, the slots of the plates being in registry with each other when the sections 17 and 17' are in the end-to-end aligned position. Circumposed on and rotatable about the section 17 of the cross-bar 15 is a locking sleeve 25, the sleeve having on one end, Figure 5A, a notch 26 which, when the sections 17 and 17' are in the end-to-end aligned position, is in alignment with the slots 24 of the plates 21 and 22. To lock the sections 17 and 17' in the end-to-end aligned position, the sleeve 25 is rotated sufficiently to cause the end portion adjacent the notch 26 to engage the registering slots 24 of the plates 21 and 22, as shown in Figures 5 and 6. Fixedly secured to the section 17 is a stop lug 27 which is engaged in a circumferentially extending slot 28 provided in the outer end of the sleeve 25 for holding the sleeve against longitudinal displacement on the section 17 and for limiting the rotary movement of the latter.

As clearly shown in Figures 4 and 7, the free or outer ends of the adjacent ones of the side bars 13 and 14 of the U-shaped bows are curved toward each other. In the embodiment illustrated, four U-shaped bows are employed, the bows being designated by the reference numerals 30, 31, 32 and 33. The bow 30 is fixed in a horizontal position, while the bows 31, 32 and 33 are pivotally connected together by means of a bolt 34 which extends transversely through the inner ends thereof for connecting the bows for movement from the divergent position of Figure 3 to the side-by-side position illustrated in phantom lines therein. Positioned at the laterally inward sides of the side bars of the outer bow 33 are the bracket plates or arms 35 and 36. Since the bracket plates are of like structure and their operative positions are the same, it will suffice to describe only one in detail.

The bracket plate 35 is in the shape of a quadrant of a circle, provided with circumferentially spaced, radially extending recesses 37 engageable with the bows 31, 32 and 33 for maintaining said bows in the extended position illustrated in Figure 1. Dependently carried by the plate 35 is a base 38 for effecting the securement of the canopy 10 to the boat 11. Suitable means are provided for clamping the bows together and against the clamping plate 35 embodying a helical spring 39 circumposed on the bolt 34 and compressed between the clamping plate 35 and lock washer 41, and a nut 40 is threaded on the bolt 34 for selectively varying the tension of the spring 39. A similar assembly including a spring 42 and a wing nut 43 is operatively connected to the bolt 34 of the clamping plate 36 for clamping the side bars 14 of the bows together and against the laterally inward side of the clamping plate 36.

Circumposed about the bows 30, 31, 32 and 33 is a cover 45 which is detachably secured to the bows by means of the pointed securing elements 46, Figure 8. As shown in Figure 1, the cover 45 is secured to the bows in such a manner that upon extension of the bows into their divergent positions with respect to each other, the cover is drawn taut.

The bases 38 on the clamping plates have depending opposed hook flanges 48 and 49 which converge toward one end thereof to provide a tapered channel 50 for receiving a wedge shaped lug 54 in a bracket 51 which may be in the form

illustrated in Figure 9, which is adapted for permanent securement to opposite sides of a boat. The bracket 51, Figure 9, is provided with spaced, screw-receiving apertures 52 and 53 for effecting the permanent securement of the bracket 51 to the boat.

In Figure 10 there is shown a modified form of the locking hinge means 20 illustrated in Figures 5 and 6. In the modified form, the sleeve 25 provided with the end notch 26 and slot 28 and the stop 27 is replaced by a sleeve 55 which is circumposed about the section 17 of the cross bar 15 and is mounted on the latter for longitudinal movement into and out of engagement with the registrable slots 24 provided in the plates 21 and 22 for locking the sections 17 and 17' in the extended position. Operatively connected to the locking sleeve 55 is a spring 56 which normally biases the sleeve 55 into engagement within the registrable slots 24, as clearly shown in Figure 10. The securement of the spring 56 to the locking sleeve and to the section 17 is effected by means of a transversely extending pin 57 which is carried by the section 17 and secured to one end of the spring. The other end of the spring abuts against the shoulder 58 provided on the sleeve 55 and thereby urges the sleeve into engagement within the registrable slots 24. When the sections 17 and 17' are to be collapsed to the position illustrated in phantom lines in Figure 4, the sleeve 55 is manually grasped and urged away from the plates 21 and 22 and out of engagement within the slots 24, whereupon the sections can be manually moved into the collapsed position.

Referring now with particularity to Figures 11 and 12, there is shown a collapsible canopy structure constructed according to the present invention which is particularly adapted for use as a vehicle top in lieu of the type of tops which employ one-piece bows. The vehicle top, generally designated by the reference numeral 60, embodies a plurality of inverted, U-shaped bows 12 arranged in spaced, parallel relation with respect to each other, and each having free ends adapted for securement at spaced intervals along the open body 61 of the vehicle. Each of the bows 12 is supported on the vehicle body by means of socket members 62 and 63 carried at spaced intervals along the opposite sides of the vehicle body 61. Secured about the bows 12 is a tarpaulin cover 64, the securement of the cover to the body being effected by any suitable means, such as the drawstrings 65. Each of the bows 12 employed in forming the vehicle top 60 includes a locking hinge 20 which enables the bows to be collapsed, as illustrated in Figure 4. It is to be noted that the locking hinge 20 employed in the several forms of the collapsible canopy structures of the present invention may be of the type employing the slotted locking sleeve 25 or the spring-biased locking sleeve 55.

Referring now to Figures 13 and 14, there is shown an awning 70 constructed according to the present invention. The awning embodies at least two bows 12, each including either type of the locking hinge means 20. The free ends of the side bars 13 of the bows 12 are connected together by an assembly similar to the one illustrated in Figure 2 and including the bolt 34, the clamping plate 35, the spring 39 and the wing-nut 40. It is to be noted, however, that the clamping plate 35 is adapted for securement to the window frame 71 on one side of the window frame. Similarly, the free ends of the side bars 14 of the bows 12 are connected together by an

assembly including bolt 34, clamping plate 36, the spring 42 and the wing nut 43, the clamping plate 36 being adapted to be secured to the window frame 71 at a point opposite the point of securement for the clamping plate 35. Secured on the bows 12 is an awning cover 72 which is drawn taut when the ribs are in their extended position at right angles with respect to each other. In the awning 70 either the type of locking hinge including the slotted sleeve 25, or the type including the spring-biased sleeve 55 may be employed.

From the foregoing, it is readily apparent that numerous other modifications of the collapsible canopy structures of the present invention can be made without departing from the spirit of the invention as set forth in the appended claims.

What I claim is:

1. In a collapsible canopy, at least two U-shaped bows each comprising a pair of laterally spaced side bars, and a two-section crossbar extending between the side bars, the sections of the crossbar being in axial alignment in the expanded condition of the canopy, the sections of the crossbar having laterally outward ends pivoted to the side bars at one end thereof, the other ends of the side bars at each side of the bows being adapted to be mounted on a support, a cover secured over the bows and extending therebetween, and locking hinge means located between and connecting the laterally inward ends of the crossbar sections, comprising plates fixed on the laterally inward ends of the crossbar sections, a pivot pin traversing said plates and connecting the plates for hinged movement relative to each other, and locking means on one of the crossbar sections engageable with the said plates for releasably locking the crossbar sections in

axial alignment, said locking means comprising radial slots formed in said plates and arranged to register with the sections in alignment, and a sleeve circumposed on one of the crossbar sections and movable thereon, said sleeve having an end arranged to engage in the slots when registered so as to lock the crossbar sections in alignment.

2. The collapsible canopy according to claim 1 including in addition a stop lug on said one section of the crossbar engaged in a slot formed in the other end of said sleeve for holding said sleeve against longitudinal displacement on said one section of the crossbar and for limiting the rotary movement of said sleeve.

3. The collapsible canopy according to claim 1 including in addition a spring operatively connected to said sleeve for normally biasing said one end of said sleeve into engagement with the slots when registered.
